UNITED STATES PATENT OFFICE.

ALFRED BERNEY, OF JERSEY CITY, NEW JERSEY.

IMPROVEMENT IN DESTROYING FORTS, &c., BY MEANS OF INFLAMMABLE LIQUIDS.

Specification forming part of Letters Patent No. 42,458, dated April 26, 1864; antedated April 19, 1864.

To all whom it may concern:

Be it known that I, ALFRED BERNEY, of Jersey City, in the county of Hudson and State of New Jersey, have invented a new and useful Means of Destroying an Enemy's Forts, Buildings, Vessels, Wharves, and Structures of all Kinds; and I do hereby declare that the following is a full, clear, and exact description of the same.

No drawings are attached to this specification, as I do not consider that the nature of the case admits of drawings, and do not deem them necessary to illustrate my invention.

It has always been thought desirable in war to possess some reliable means of setting on fire towns, shipping, and works of every nature held by an enemy. Many attempts have been made to produce some efficient instrumentality for this purpose; but previous to my invention none of them have succeeded, with the exception, perhaps, of what is called the "Greek fire," and the preparation and mode of using that substance has long been one of the "lost arts," and at the present time is wholly a matter of conjecture. Modern nations have not, however, relaxed their efforts to provide themselves with a similar instrument of offence; but hitherto nothing of the kind more formidable than fire-stone, carcasses, hot shot, incendiary rockets, and some other defective weapons of that class is known to military science, and none of these are now considered properly adapted to the exigencies of warfare. The two obvious and leading requisites of an efficient agent of the character referred to are, first, that it shall possess the property of being highly inflammable and readily and completely ignited, adapted to burn with fierceness and persistence, to spread rapidly, and communicate fire instantaneously to everything combustible with which it comes in contact, and shall be able to burn upon metal or water, or, if necessary, within a confined space; and, second, that it shall be capable of being projected to a considerable distance, so as to reach an enemy at a point beyond that to which the troops using it have penetrated.

My invention therefore consists in providing a material which possesses the characteristics above enumerated, and in combining therewith proper machinery for throwing it

rapidly and in large quantities over as great a space as possible.

To this end I employ the liquid described in certain Letters Patent of the United States granted to me on the 11th day of November, 1862, and entitled "for an improved liquid-fire shell or projectile," and for projecting it I use any of the suitable varieties of modern forcing-pumps—such, for instance, as Worthington's pump, Cary's rotary pump, or any good double-acting pump. A strong reservoir, made of boiler-plate, should be provided to contain the liquid. From this it is to be drawn by the pump, and upon leaving the latter it is forced through a strong tube, and is discharged from a suitable nozzle against the object to be set on fire, the liquid being inflamed by a match or torch at about the point at which it leaves the nozzle. In this way I am enabled to throw upon an enemy's position a hundred or more gallons per minute of a liquid which possesses all the properties before specified. The effect of this as a weapon of offensive or defensive warfare will be obvious. Nothing at all combustible can stand before it, and when projected against a column of troops it will not only produce immense destruction of life, but it will tend to spread terror and panic through their ranks. The apparatus for containing and throwing it may be with very great ease transported or maneuvered on the field of battle. By reason of its comparative lightness it can be employed where batteries or single guns could not be carried, and from its nature it furnishes to the troops managing it a far more effectual safeguard against its capture than artillerists possess. As this liquid will burn fiercely within a confined space, and emits a dense smoke and stifling odor, it will be of great service in attacking even iron-clad vessels, as a sufficient quantity of it may easily be thrown in a short time upon them to fill their entire interior with a solid mass of fire, in which no crew of course could live, and which would speedily, by exploding the magazine, destroy the ship.

In making use of my invention at sea I propose to place the apparatus for making it upon a vessel properly protected against hostile shot, either by iron armor or in any other manner; but of course the construction and ar-

angement of such a vessel may be varied at pleasure, and has nothing to do with the invention here described.

Upon land I contemplate using, if desired, a strong iron shield, of any suitable form, made so as to be impenetrable to missiles, and which will cover my apparatus, and may be capable of being pushed by troops over a field of battle for the purpose of attacking batteries or works of an enemy. The shield will protect the men accompanying it, who may be armed to repel assaults.

I also contemplate reducing the danger of accidents to troops using my invention by throwing, after the flame is once started, only crude petroleum—what is known as “dead-oil”—or any other inflammable oil which is not in itself explosive, but which will suitably sustain the fire which has been originated by the liquid already referred to. By this means

I am enabled to use a smaller quantity of the latter, and thereby render my invention more safe in practice, especially upon shipboard.

I claim—

1. The above-described means of inflicting injury upon an enemy by employing the liquid referred to, or any equivalent therefor possessing the properties above enumerated, in combination with suitable machinery for projecting the same to a distance, substantially as set forth.
2. Using only the said crude petroleum or said oil, or another inflammable oil, for the purpose specified after flame has been originated, in the manner substantially as set forth.

ALFRED BERNEY.
